Attorneys.

UNITED STATES PATENT OFFICE.

GROVER BAKER, OF TEMPLE HILL, ILLINOIS.

SWINGING SCAFFOLD.

Application filed March 8, 1922. Serial No. 542,098.

To all whom it may concern:

Be it known that I, GROVER BAKER, a citizen of the United States, residing at Temple Hill, in the county of Pope and State of Illinois, have invented or discovered certain new and useful Improvements in Swinging Scaffolds, of which the following is a specification, reference being had therein to the accompanying drawing.

10 This invention relates to a swinging scaffold more especially intended to be suspended in the upper part of a hay or grain barn in convenient position for use in putting up or adjusting a hay carrier which is to be located in the top of the barn. The improved scaffold comprises supporting rods provided at their upper ends with hooks to be engaged with the rafters of the barn between the boards constituting the sheathing on which 20 the shingles or other roof coverings are laid, these boards being usually spaced apart so that the hooks may engage the rafters between the same; or the hooks may be engaged with suitable staples or the like driven into 25 or bolted to the rafters. The supporting rods are bent into suitable shape at their lower ends to afford stirrups adapted to hold a board which will extend between said supporting rods. Jointed to each of the 30 stirrups is a rigid brace rod adapted to be hooked into a staple or the like secured to a rafter or other suitable support, these brace rods being for the purpose of holding the scaffold steady when in use. The scaffold is intended to be made in sections extending the entire length of the barn so as to afford convenient access to a hay carrier when adjusted to different positions lengthwise of the barn in which said hay carrier 35 may be mounted. To each scaffold section is preferably connected a rope running over a pulley suspended from a rafter or the like, said rope extending downward so as to be conveniently accessible from below and 40 by means of this rope the scaffold, when not in use, may be swung upward close to the rafters and out of the way of the hay carrier, the scaffold being held in such out-of-the-way position by securing the end of the 45 rope below, or in any other suitable manner.

50 In the accompanying drawing Fig. 1 is a perspective view illustrating the invention. Fig. 2 is an end view showing the scaffold in full lines in working position, and in dotted lines when swung up out of the way.

Fig. 3 is a detail view of one of the hooked supports and its brace rod.

Referring to the drawing, 12 denotes one of the scaffold supports which preferably 60 consists of a metal rod provided at its top with a hook 13 and at its lower end with a looped stirrup 14. Jointed to each stirrup 14 is a brace rod 15 preferably provided with a hook 16. The hooks 16 are, in practice, engaged with staples or the like mounted on the rafters or other parts of the roof, as hereinbefore stated, and as indicated in the drawing, and thus serve to steady and hold the scaffold positively in working position. These scaffold supports when in use are intended to be suspended from the rafters 17 of the barn, either by being hooked directly on to said rafters between the sheathing boards or by being engaged with 70 other suitable supports attached to the rafters. The stirrups 14 are intended to support and enclose a board, as 18. In practice a plurality of these swinging scaffolds extending practically the entire length of the 80 barn will be provided for use in putting up and adjusting the hay carrier. Connected with each scaffold section is a rope 19 passing over a pulley 20 and by means of which rope, which extends down so as to be conveniently 85 reached from below, the scaffold may, when not in use, be swung up close to the rafters and maintained in such position by securing the end of the rope to a nail or cleat down below.

90 From the foregoing it will be understood that the invention provides a suitable scaffold intended to remain permanently in place and by means of which convenient access to a hay carrier is afforded, thus obviating the inconvenience of sending up a man to climb along on the track of the hay carrier in adjusting or fixing the same. The sections of the improved scaffold are intended to extend practically the entire 100 length of the hay carrier track so as to afford convenient access to the hay carrier at any point along said track, for fixing or adjusting the hay carrier. When the scaffold is not in use it can be swung up and maintained in position out of the way so as not to interfere with the hay carrier.

Having thus described my invention, I claim and desire to secure by Letters Patent:

110 1. The herein described swinging scaffold, for use in hay barns or the like, comprising

- supports each consisting of a rod shaped to provide a hook at its upper end and a looped stirrup at its lower end, these stirrups being of suitable size and shape to receive a board 5 to serve as the scaffold platform, combined with rigid brace rods connected with said stirrups and by means of which the scaffold may be positively steadied and held in working position.
- 10 2. The herein described swinging scaffold, for use in hay barns or the like, comprising supports each consisting of a rod adapted to provide a hook at its upper end and a

looped stirrup at its lower end, these stirrups being of suitable size and shape to receive a board to serve as the scaffold platform, combined with rigid brace rods connected with said stirrups and by means of which the scaffold may be positively steadied and held in working position, comprising a rope and pulley, for swinging the scaffold up out of the way, when not in use, and securing it in swung-up position.

In testimony whereof I affix my signature:

GROVER BAKER.
